(57) CLAIM

The ornamental design for digital audio disc player for automobile, as shown and described.

DESCRIPTION

FIG. 1 is a perspective view of front, right and top of digital audio disc player for automobile showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating the unclaimed portions of digital audio disc player for automobile and form no part of the claimed design.
